UNITED STATES PATENT OFFICE.

FRANK PARDEE AND FRANK PARDEE, JR., OF HAZLETON, PENNSYLVANIA, ASSIGNEES TO ANTHRACITE SEPARATOR COMPANY, OF HAZLETON, PENNSYLVANIA, A CORPORATION OF PENNSYLVANIA

LOWERING CHUTE.

Application filed June 15, 1928. Serial No. 285,540.

The present invention relates to spiral lowering chutes for conveying material from a higher to a lower level, the chute illustrated being particularly adapted for piling 5 coal in storage yards or silos although not limited to such use. Chutes of this general character heretofore constructed have been supported by means of a skeleton framework usually including a plurality of uprights arranged 10 on the exterior of the conveyor thread and tied to one another by cross-bracing so as to stiffen the skeleton structure against lateral deflection. In other types, the conveyor has been supported by means 15 of an axial post having radially extending rods to which the runway of the conveyor was secured. In another form of construction, the chute included a plurality of uprights having a stiff spiral flange secured to 20 and forming the sole bracing for the uprights and a runway supported on brackets secured to the spiral flange and the uprights.

The present invention aims to provide improvements over the former constructions 25 and involves the use of a rolled metal section having an inwardly extending flange adapted to support substantially flat segmental plates forming part of the runway. The present improvement also provides an upper 30 inwardly extending guard flange which serves to prevent the material travelling along the runway from climbing up and spilling over the outer edge thereof.

The invention will be fully apparent 35 from the following specification when read in connection with the accompanying drawings and will be defined with particularity in the appended claims. In the drawings—

Fig. 1 is a side elevation of the upper end 40 of a lowering chute embodying our invention;

Fig. 2 is a plan view thereof;

Fig. 3 is a diagrammatic view in section 45 of one of the channel sections;

Fig. 4 is a section on line 4—4 of Fig. 2;

Fig. 5 is a similar section illustrating a slight modification;

Fig. 6 is a view of an alternative embodiment 50 of the invention;

Fig. 7 is a view at right angles to Fig. 6;

Figs. 8, 9 and 10 illustrate modifications.

Referring in detail to the drawings, we provide a pair of diametrically arranged up-

rights 10—10 which in the form illustrated 55 are rolled structural channel sections. Bolted or otherwise secured to these uprights, we provide a spiral shaped rolled member 12 preferably having an inwardly extending flange 14 and an integral web 16.

The rolled member 12 may be formed in 60 separate parts each making one turn or convolution or a fraction of a convolution, the parts being suitably spliced together by means of connection plates 18 such as indicated in Fig. 2, the ends of the different parts making a butt joint 20 and being bolted to the upright as shown. The inwardly extending flange 14 of the member 12 provides 65 means whereby the runway can be supported 70 in an inwardly and downwardly inclined position. As shown in the drawings, the runway is composed of a series of substantially 75 flat segmental plates 22 which are secured near their outer edges to the flange 14 by means of bolts 24. The lower end 26 of each section overlaps the upper portion 28 of the section next below and they are joined by a bolt or rivet as indicated at 30 near the 80 inner edge of the runway.

The spiral member 12 of Figs 1 and 3 being of substantially channel shape in cross-section includes an upper flange 32 which serves as a guard preventing the material travelling on the runway from climbing up 85 and spilling over the outer edge thereof. The flanges 14 and 32 also serve to greatly rigidify the structure transversely. And because of this rigidity, the entire structure can be supported solely by two uprights 10. 90 Or in some cases by using a slightly heavier channel section 12, the uprights may be dispensed with by merely securing suitable lateral braces to any adjacent fixed structure and attaching them to the channel member 95 12.

It is desirable in lowering chutes to have the runway so supported that the outer portion thereof, in a radial line, is higher than the inner edge thereof. In other words, 100 it is preferable to have the runway inclined inwardly and downwardly so as to assist in preventing the material handled from choking the conveyor runway and also to provide such an inclination that the material 105 handled will be discharged easily by gravity in an inner direction.

Heretofore to secure this inclination it

has been found necessary to provide specially shaped brackets. In the present design we take advantage of the natural inclination of the inner face of the flange of the rolled member and we have discovered that by rolling a stock rolled structural member to a spiral form that the web portion 16 is slightly bowed as indicated at *b* in Fig. 3 and the flanges 32 and 14 due to this bowing are distorted so that their outer edges are flared out of parallel as indicated on the exaggerated scale by lines *c-d*, and *e-f* in Fig. 3. This has a tendency to increase the downward inclination of the inner face of the flange 14 so as to provide a properly inwardly inclined seat for the outer edges of the segmental plates 22 of which the runway is formed.

Instead of supporting the runway plates on the flange of a rolled channel shaped member, we may use other flanged rolled members such as angles or the like. For example, in Fig. 5, we have shown a modification in which the spiral member 12^a is in the form of a so-called bulb-angle having a runway supporting flange 14^a and an upper bulbous shallow flange 32^a.

At the upper end of the apparatus, a suitable inclined feed chute 34 is provided which delivers coal or other material to be handled to the upper part of the runway.

An alternative embodiment of the invention is illustrated in Figs. 6 and 7 wherein the uprights 10-10 are dispensed with and the spiral structure is self-supporting. In this form of chute, the spiral shaped rolled member 12 will be of slightly heavier weight per unit of length than that shown in Fig. 1. Near the lower end of the structure, short supporting brackets or legs 36 will be bolted or otherwise secured as indicated at 38 to the web portion of the rolled member 12. These legs will be provided with feet 40 anchored to a supporting base 42.

In some cases, the lowering chutes will be secured to the floors of storage bins. These bins in practice are of different form and the supporting legs 36 can be formed to suit. For example, in Fig. 8, we have shown the legs 36 having the feet 40^a disposed at proper angle to engage the inclined surfaces of the flooring of a V-shaped bin 44. Fig. 9 illustrates how the self-supporting spiral may be secured to the inclined floor of a bin or other structure, the legs 36^b in this form having the under surfaces of their feet 40^b all inclined at the same angle to the horizontal.

Fig. 10 shows a further modification in which the legs 36^c have their feet 40^c bent to engage the inclined surfaces 46 of the floor of a bin formed like an inverted V.

The improved piling chute herein described is devoid of all cross-bracing and the runway is supported at its outer edge solely

by the inwardly extending flange of the rolled structural member. Thus, there are no braces, brackets or other external members against which the material discharged will strike. Lowering chutes of the class 70 described are frequently used for piling coal in storage silos or other enclosures where there is no provision for heating and frequently the coal is handled wet and the entire mass freezes or solidifies. With our 75 improved lowering chute which is devoid of cross-bracings and in those forms which are also devoid of uprights, there is much less tendency to block the flow of coal from the coal pocket or bin than exists in the structures heretofore provided which offer many 80 projections and crevices for the coal to freeze fast to and thus obstruct the flow of coal from the pocket and make it extremely difficult to clean the same.

While we have described quite specifically the embodiments of the invention illustrated, it is not to be construed that we are limited thereto since changes in arrangement and substitutions of equivalents may be made by 90 those skilled in the art without departing from the invention as defined in the appended claims.

What we claim is:—

1. A spiral chute comprising a plurality of uprights, a spiral section secured thereto having an integral web and an inwardly projecting flange and a spiral runway including a series of metal plates secured to the inner face of said flange adjacent said web. 95

2. A spiral chute including a rolled metal spiral section having an integral web and an inwardly projecting flange and a spiral runway supported solely by said flange.

3. A spiral chute including a rolled metal spiral section having an integral web and an inwardly projecting flange and a spiral runway supported solely by said flange, said section having an inwardly extending guard flange spaced above the first mentioned flange. 105

4. A spiral chute including a rolled metal spiral section having an integral web and an inwardly projecting flange and a spiral runway comprising a series of substantially flat segmental metal plates secured at their outer edges to the inner face of said flange, said plates being inclined inwardly and downwardly. 115

5. A spiral lowering chute comprising only two oppositely disposed uprights, a spiral rolled section having an integral web and flange, the web being secured directly to said uprights, and a runway comprising a series of substantially flat segmental metal plates secured at their outer edges to the inner face of said flange, said plates being inclined and downwardly. 120

6. A spiral lowering chute including a spiral runway supporting member of chan- 130

nel shape in cross-section, the lower flange of said channel shaped member having a series of segmental plates secured thereto to form a runway, the upper flange of said member forming a guard to prevent the material from climbing over the outer edge of said member.

7. A spiral lowering chute including a pair of uprights, a rolled metal section having its web secured directly to said uprights and an upper inwardly extending guard flange and a lower inwardly extending supporting flange and a runway comprising a series of substantially flat segmental plates secured at their outer edges to said supporting flange.

8. A spiral chute including a rolled metal spirally formed channel section having a bowed web portion and slightly flaring flanges, the inner faces of said flanges being inclined with respect to their outer faces and a spiral runway comprising a series of segmental plates secured at their inner edges to the inner inclined face of one of said flanges.

9. A spiral chute comprising a rolled metal flanged section of spiral form having a series of overlapping plates secured to one another and to a flange of said section and bracing the structure so that it is self-supporting.

10. A spiral chute comprising a rolled channel section of spiral form having a series of overlapping plates secured to one another and to a flange of said section and bracing the structure so that it is self-supporting.

11. A spiral chute comprising a roller metal flanged section of spiral form having a series of overlapping plates secured to one another and to a flange of said section and bracing the structure so that it is self-supporting and a base member secured to said section so that the structure is capable of standing upright without external support.

In witness whereof, We have hereunto signed our names.

FRANK PARDEE.
